LANDSCAPE PLANNING RULE

Clarence A. Vanderbrook and Wilford C. Jaynes,
Newark, N. Y., assignors to C. W. Stuart &
Company, Inc., Newark, N. Y., a corporation of
New York

Application February 25, 1948, Serial No. 144,724

Term of patent 14 years

(Cl. D52—1)

To all whom it may concern:

Be it known that we, Clarence A. Vanderbrook and Wilford C. Jaynes, citizens of the United States, residing at Newark, in the county of Wayne and State of New York, respectively, have invented a new, original, and ornamental Design for a Landscape Planning Rule, of which the following is a specification, reference being had to the accompanying drawing, forming a part thereof in which:

Fig. 1 is a plan view of a landscape planning rule, showing our new design;

Fig. 2 is an edge view thereof.

We claim:

The ornamental design for a landscape planning rule, as shown.

CLARENCE A. VANDERBROOK.
WILFORD C. JAYNES.
